HEATING DEVICE ADAPTED TO
ELECTRIC RANGESAngus W. McIntyre, Victoria, British
Columbia, CanadaApplication March 10, 1948, Serial No. 14,013
In Canada February 13, 1948

1 Claim. (Cl. 219—39)

1

My invention relates to improvements in heating devices, more particularly to a heating unit adapted to electric ranges.

In a great many homes, some form of heating is required for the greater part of the year, and those homes that have no furnace outlet require some form of auxiliary heating system, and those that have a radiator in the kitchen face the same problem in the cool early hours of the morning during those months when the furnace is not in use.

My invention can either be built as part of a new range or adapted to existing full size or apartment model electric ranges.

Electric ranges are usually made to rest on a base called toe cove base of approximately six inches in height. It covers the entire surface of the stove except for a narrow free strip at the front thereof, the purpose of which being to make it possible for the housewife to stand closer to the range for convenient working.

It is this supporting base of the range which I propose to use or convert, as the case may be, into an economical way of heating the room in which the electric range is installed by means of a unit installed in part of the base of existing ranges or sold as part of new ranges.

My invention consists of a heating device placed in the toe cove base of electric ranges as aforesaid, and it comprises one or more elements electrically heated and enclosed in a housing which itself is resting on an insulated plate on the bottom face of the base of the range.

A small blower, also part of the unit, draws air through openings provided in the back face of the base and blown through the housing over the heating elements and finally out of the housing on to the floor through a grill. The blower is actuated by means of an electric motor also placed in the housing, the motor and the heating elements being connected to the electric wiring of the stove in built-in units, or to the house circuit if added to an existing stove with a separate remote controlling switch, not shown.

The principal object of my invention is to provide means by which moderate heat will be supplied in a kitchen, at a low cost, and quickly when needed and without danger of fire as it often happens with ordinary floor heaters.

Other objects of the invention will appear as I proceed with the description, and I attain these objects by the device illustrated in the accompanying drawing in which:

Figure 1 shows the front elevation of an electric range; Figure 2 shows a sectional plan of the device through the heater and blower assembly taken at 2—2 of Figure 3; and Figure 3 shows a sectional elevation through the heater at 3—3 of Figure 1.

2

Similar numerals refer to similar parts throughout the several views.

The housing 10, the heating elements 7, the blower assembly 17 and the grill frame 5', constitute the main parts of the device, the whole being supported by an insulated plate 24 placed a short distance from the floor of the kitchen.

Numeral 5 shows the toe cove base of an electric range into part of which I place the entire heating arrangement.

The housing 10 is made in two united sections, the front section being rectangular and containing the heating element 7; the other or rear section 11 having substantially the form of a cone, the apex 19 of which being joined to the outlet of the blower 17 by means of a flexible coupling tube 16. The blower is operated by a small motor 23 through drive shaft 20 and held in place by means of plate 24 and base 21.

The heating elements 7 are secured to angle members 8—9 secured to the side walls of the housing.

Numeral 15 represents the rear panel of the stove, and 15' designates the rear panel of the toe base. In rear panel 15', I provide air inlets 15''. Numeral 22 shows the vertical separating wall in the stove structure; and 18 also shows a dividing plate between the toe base and the upper part of the range containing warming drawer 13, and 12 is the door of the range warming closet.

In the front wall of the toe cove base opposite the part used to contain the heating unit, is a grill frame 5', and in that frame I provide a number of louvres 6 for directing heated air on the floor of the kitchen.

I claim:

A heating device in combination with the toe cove base of an electric range, a housing secured in said base and consisting of two integral sections, one of said sections being rectangular and the other being funnel shaped and flexibly connected to a blower, angle members secured on the side walls of said rectangular section of the housing and supporting heating elements, a grill in the outer face of the base, said housing resting on an insulated plate, as shown and described.

A. W. McINTYRE.
